HUBERT M. FREEMAN, OF EAST PITTSBURGH, PENNSYLVANIA, ASSIGNOR TO WESTINGHOUSE ELECTRIC & MANUFACTURING COMPANY, A CORPORATION OF PENNSYLVANIA

VACUUM-TUBE DEVICE

Application filed November 7, 1922, Serial No. 599,497. Renewed November 27, 1929.

My invention relates to vacuum-tube devices and more particularly to the structure of such devices.

The principal object of my invention is to provide a vacuum-tube construction comprising an equipotential cathode element and an exciting element therefor, wherein the potential of the cathode element is substantially independent of the alternating currents supplied to the exciting element.

Another object of my invention is to provide a vacuum-tube construction of the class described, embodying a design wherein the cathode element is connected directly to the grounded point of such circuits as are associated therewith, thereby increasing the efficiency of operation of the tube by avoiding capacity effects between the cathode element and the other elements of the system and ground.

In the design and manufacture of detecting or amplifying vacuum tubes of the above-mentioned class prior to my present invention, the usual practice has been to connect the equipotential cathode element directly to one of the supply leads for the exciting element, within the evacuated portions of the tube. Such connection makes possible a vacuum-tube construction wherein only four terminal pins are required.

In practice, it has been observed that when a single tube having the above-mentioned internal cathode connection was employed, the usual so-called "alternating-current hum" was entirely absent in the operation of the tube. However, when a number of such tubes were connected in cascade, there appeared an appreciable alternating-current hum which was very troublesome.

After considerable experimental work, I have found that the above indicated difficulties are due to the fact that the alternating-current supply circuit for the heater element imparts, to the equipotential cathode member, a varying potential which is represented by the drop in potential in the portions of the heater supply circuit between the contacting surface of the terminal pin and the point of connection of the equipotential cathode element to the supply circuit.

The above-mentioned undesirable results are avoided in my invention by connecting the lead from the equipotential cathode element directly to a point which is common to the input and output circuits of the vacuum-tube and to the heater supply circuit,—viz., to the contacting surface on one of the heater supply-circuit terminal pins.

With these and other objects and applications in view, my invention further consists in the details of construction and arrangement hereinafter described and claimed and illustrated in the accompanying drawing, wherein:

Figure 1 is a perspective view of a vacuum-tube device embodying my invention together with suitable operating circuit connections, a portion of the vacuum-tube containing walls being broken away and the plate and grid elements being shown partly in longitudinal section,

Fig. 2 is an enlarged detail longitudinal sectional view of the cathode construction shown in Fig. 1, and

Fig. 3 is a diagrammatic view of circuits and apparatus embodying my invention.

In the form of embodiment of my invention shown in the drawing, I provide an elongated tubular container 1 having a re-entrant portion 2 terminating in a supporting press 3. A cathode construction 4 comprises a mass of refractory material 5 in the form of an elongated solid cylinder having a pair of adjacently positioned perforations 6 and 7 extending longitudinally therethrough. The perforations 6 and 7 are of such dimensions as to receive a filamentary element 8 which is inserted up through one perforation and down through the other to provide a filament of substantially inverted U shape, comprising parallelly extending portions 9 and 11 and a bent portion 12.

The distance between the parallel portions 9 and 11 of the filament 8 is so small that the magnetic field established by currents traversing one portion or section substantially neutralizes the magnetic field established by currents traversing the other section, thereby minimizing the effect of the alternating supply currents upon the operation of the vacu-

um-tube device. The filament 8 may be energized by connecting the same to the two filament supply conductors 13 and 14 which are supported in the press 3 and which are provided with external extensions 15 and 16, respectively.

The cylindrical member 5 is preferably made of some insulating refractory material which, when heated to the temperature of the heater element 8, is free from chemical action therewith. In the course of much experimental work, I have found that zircon in combination with a binding material, as clay, possesses such desirable characteristics.

A member 17, which forms the equipotential cathode surface, is shown in the form of a tube having its inner surface rigidly embracing the tubular insulating member 5. The outer surface of the member 17 may be coated with oxides of barium and strontium or with other substances which, when subjected to heat, are rendered thermionically active.

The cathode construction may be supported by means of a carrier rod 18 extending from the press 3 and secured thereto as hereinafter described. In practice, it has been found desirable to provide a spring connection between the cathode construction 4 and the supporting carrier rod 18 in order to provide for the expansion and the contraction of the heating element 8. The desired resilient mounting for the cathode construction 4 may be obtained by welding a strip 19 to the upper end of the cathode construction, preferably to the tubular member 17, and by interconnecting the strip 19 and the carrier rod 18 by means of a resilient member 21. The strip 19 is insulatingly spaced from the heater element 8 to prevent the carrier rod 18 being impressed with varying potentials from the heater element 8. The carrier rod 18 may be extended through the press to provide an external connection 22 for the equipotential cathode member 17.

The cathode construction 4 may be surrounded by plate and grid elements 23 and 24 of conventional design. By way of illustration, the grid 24 is shown helical in shape with its longitudinal axis co-inciding with that of the heater element 8. The grid 24 is supported in position by means of a carrier rod 25 extending from the press 3 and welded to the several helices of the grid to impart additional stiffness to the grid construction.

The cylindrical plate 23 is symmetrically positioned with respect to the previously mentioned elements and is supported by carrier rods 26 and 27 which are mounted in the press 3, one of the carrier rods, say 27, being extended through the press 3 to provide an external circuit terminal 28.

The envelope 1 may be provided with a base 29 which comprises a circular insulat-

ing member 31 and a collar 31a, opposite ends of the latter rigidly embracing the re-entrant tube 2 and the insulating member 31 in any approved manner. The lower end of the insulating block 31 may be provided with a plurality of hollow terminal pins 32 and 33, 34 and 35. The several external connections 15, 16, 22 and 28 are disposed in the hollow portions of the terminal pins in such manner that terminal pins 32 and 33 are connected to the heater element 8 and the pins 35 and 34 are connected to the plate and grid elements, respectively. A perforation 36, which extends through the insulating block 31, may be positioned immediately adjacent to the terminal pin 33 for reasons which will appear hereinafter.

As pointed out in the foregoing portions of the specification, it is desirable that the equipotential cathode member 17 be connected to the heater supply circuit at a point which is common to the input and the output circuits of the vacuum tube and to the heater supply circuit. Such desired result is obtained by extending the external connection 22 from the equipotential cathode member 17 through the perforation 36 in the insulating block 31 and securing said connection to the contacting surface of one of the heater supply terminal pins, say 33. Such construction avoids any possibility of the occurrence of a variable potential on the equipotential cathode member 17 as a result of impedance drops in the heater supply conductors within the tube.

When the tube above described is inserted in a socket having connections to the circuit described in detail in connection with Fig. 3, the socket connections will be as indicated at the bottom of Fig. 1. The reference numerals indicating the circuit element in Fig. 1, have the meaning stated for the same numerals in Fig. 3.

Fig. 3 is a diagrammatic view of a vacuum-tube construction embodying my invention, together with circuit connections whereby the tube may function as an amplifier of alternating currents. The grid 24 and the equipotential cathode member 17 are connected, by input conductors 37 and 38, respectively, to a source of incoming signals (not shown). A plate-filament circuit, or so-called "outgoing circuit", 39 extends from the plate 23 to the equipotential cathode element 17 and includes a detecting device 41 and a source 42 of direct-current energy. The input circuit formed by the conductors 37 and 38 and the outgoing circuit 39 are interconnected at a common junction point 43. A source of alternating-current energy (not shown) of commercial frequency is operatively connected to the heater element 8 through a transformer 44. The supply circuit of the heater element 8 is connected to the junction point 43 of the input and output circuits to form a common junction point for the three circuits which

corresponds to the contacting surface of the terminal pin 33. The cathode structure 4 may be connected to ground by means of the ground conductor 45 extending from the common junction point 43 of the several circuits.

5 While I have shown a single embodiment of my invention, for the purpose of describing the same and illustrating the construction and operation thereof, it is apparent that 10 various changes and modifications may be made therein without departing from the spirit of my invention. I desire, therefore, that only such limitations shall be imposed thereon as are indicated by the appended 15 claims or demanded by the prior art.

15 I claim as my invention:

1. The combination with a tube having an equipotential cathode member and a separate heater element, of a base for said tube carrying a pair of terminal pins for said heater 20 element, said member being directly connected to one of said terminal pins.

2. A space-current device comprising a tube having an equipotential cathode member and a heater element, a base for said tube comprising an insulating member, a pair of terminal pins having contact surfaces carried by said insulating member, and means connecting said terminal pins to said heater 30 element and means connecting said cathode member to the contacting surface of one of said pins.

3. In combination, a space-current device comprising an anode element, a cathode element, a controlling element and energizing means for said cathode element, interconnected input and output circuits for said elements having a single junction point, an exciting circuit for said energizing means, said 35 exciting circuit being connected to said first-mentioned circuits at said junction point, and means for grounding said junction point.

4. In combination, a space-current device comprising an anode element, a controlling 45 element, a cathode element and energizing means for said cathode element, said energizing means comprising a looped filament, interconnected input and output circuits for said elements having a single junction point, an exciting circuit for said energizing means, said 50 exciting circuit being connected to said first-mentioned circuits at said junction point, and means for grounding said junction point.

5. In combination, a space-current device 55 comprising an anode element, a controlling element, a cathode element and energizing means for said cathode element, said energizing means comprising a V-shaped filament, interconnected input and output circuits for said elements having a single junction point, an exciting circuit for said energizing means, said 60 exciting circuit being connected to said first-mentioned circuits at said junction point, and means for grounding said junction point.

6. In combination, a space-current device

comprising an anode element, a control element, a cathode element and energizing means for said cathode element, said energizing means comprising a looped filament, an input circuit connected to said control element and said cathode element, an output circuit connected to said anode element and said cathode element whereby said circuits have a common junction point, an exciting circuit for said energizing means, said exciting circuit being connected to said first-mentioned circuits at said junction point, said filament having one leg thereof directly connected to said junction point, and means for grounding said junction point.

7. In combination, a space-current discharge device comprising an anode element, a control element, a cathode element and energizing means for said cathode element, an input circuit connected to said control element and said cathode element, an output circuit connected to said anode element and said cathode element whereby said circuits have a common junction point, an exciting circuit for said energizing means, said exciting circuit being connected to said first-mentioned circuits at said junction point.

8. In combination, a space-current discharge device comprising an anode element, a control element, a cathode element and energizing means for said cathode element, an input circuit connected to said control element and said cathode element, an output circuit connected to said anode element and said cathode element whereby said circuits have a common junction point, an exciting circuit for said energizing means, said exciting circuit being connected to said first-mentioned circuits at said junction point and means for grounding said junction point.

9. In a tube having an equipotential cathode member and a separate heater element, terminal members for said heater element, and a direct electrical connection between said cathode member and one of said 100 terminal members.

10. In a tube having an equipotential cathode member and a separate heater element, terminal members for said heater element, and means for maintaining said cathode member and one of said terminal members 105 at the same potential.

11. An electron-discharge device comprising an evacuated vessel, an equipotential cathode member and a separate heater element therefor positioned inside said vessel, terminal members for said heater element positioned outside said vessel, and means for maintaining said cathode member and one of said terminal members at the same potential.

In testimony whereof, I have hereunto subscribed my name this 27th day of October, 1922.

HUBERT M. FREEMAN.
